GRAB BUCKET

William H. Ray, Vandergrift, Pa., assignor to United States Steel Corporation, a corporation of New Jersey

Application December 18, 1957, Serial No. 703,620

6 Claims. (Cl. 37—184)

The present invention relates generally to apparatus for handling material and more particularly to an improved grab bucket especially suitable for use with lift cranes and the like for hoisting and conveying bulk materials such as earth, coal, sand, etc.

Prior to my invention grab buckets were usually one or the other of two conventional types. In one type the bucket was suspended by one cable and a second cable was used to operate the opening and closing mechanism of the bucket. In the other type, the bucket was suspended by a cable and the bucket opening and closing mechanism was operated by an electric hoist mounted on the bucket. Neither of these two types of grab buckets could be used effectively on the lift hook of an electric overhead traveling crane unless the crane was equipped with a special winding drum to control the opening and closing mechanism operating cable of the first type or the electrical power cable of the hoisting mechanism of the second type.

It is, accordingly, a primary object of my invention to provide a grab bucket for use with a lift crane which may be suspended from the lift hook of the crane by means of a bail so arranged with respect to the suspension means of the bucket that the bucket can be opened and closed by horizontal movement of the bail.

This and other objects will become more apparent after referring to the following specification and attached drawings, in which:

Figure 1 is a vertical sectional view showing the grab bucket of the invention in closed position;

Figure 2 is a view similar to Figure 1 showing the bucket in open position;

Figure 3 is a vertical sectional view taken on the line III—III of Figure 1;

Figure 4 is a partial vertical sectional view taken on the line IV—IV of Figure 2;

Figure 5 is a view similar to Figure 4 showing the bail of the bucket in an intermediate position; and

Figure 6 is a view similar to Figure 5 but looking toward the opposite side of the support housing showing the bail partially raised in engagement with the curved guide.

Referring more particularly to the drawings reference numeral 2 designates generally the grab bucket of the invention suspended from the lift hook 4 of a crane (not shown).

The grab bucket 2 includes a pair of hinged bucket halves 6 having inner edges 8 adapted to mate so that the halves form a receptacle when brought together, as shown in Figure 1. The upper portions of the inner edges 8 of the halves 6 are in the shape of flanges 10. The flanges of one bucket half overlap and slidably engage the flanges of the other bucket half, as best shown in Figure 2. The flanged portions 10 of the bucket halves are hinged on a common shaft 12 which has its ends journaled in the overlapping flange portions 10 and extends transversely of the grab bucket adjacent its upper edge.

2

Each of the bucket halves 6 is formed with spaced side walls 14 and an outer end wall 16 which extends between the bottom and outer edges of the spaced side walls of each bucket half.

5 A support housing 18 which is provided with four sides is disposed above the bucket halves and is provided with a pair of spaced inner walls 20 which define spaces 22 on two sides of the support housing. A pair of spaced pivot pins 24 are mounted on each of the inner walls 20 and extends therefrom through the space 22 and the outer wall of the support housing adjacent thereto.

A rigid support rod 26 is pivotally mounted by its upper end on each of the pins 24 and depends downwardly therefrom toward the bucket halves 6.

15 A transversely extending support shaft 28, which may be square in cross-section, is rigidly supported by its ends in the spaced side walls 14 of each bucket half by means of mounting plates 30.

A pair of spaced dogleg lever arms 32 are rigidly 20 mounted on each of the support shafts 28. The lever arms 32 are mounted intermediate their ends and extend normal to their respective shafts 28. The bottom ends of each of the rigid support rods 26 is pivotally connected with the end of a lever arm toward the outer end wall of 25 its respective bucket half, as best shown in Figures 1 and 2.

The grab bucket 2 of the invention is supported on the lift hook 4 by means of a bail 34 which is disposed above the bucket halves 6 for vertical and horizontal movement 30 in the support housing 18. Two pairs of cables 36, which may be in the form of chains, are pivotally attached by their upper ends to the bottom of the bail 34 and depend therefrom toward the bucket halves 6. The bottom ends of the cables 36 are attached one to the end of each of the 35 lever arms 32 toward the inner edges of the bucket halves.

The bail 34 is relatively flat and is provided with an intermediate portion 40 of reduced cross-sectional area forming laterally extending upper shoulders 42 and laterally extending lower shoulders 44.

40 A bottom-slotted, vertically split lift block 46 is provided on the interior of support housing 18 between the inner walls 20 on one side of the vertical center line of the support housing, as best shown in Figure 2. The lift block 46 is formed by two spaced projections on the interior of one of the side walls 48 of support housing 18 which extend normal to the inner walls 20.

A vertically split curved guide is formed by ribs 50 on the interior of the wall of support housing 18 opposite to the wall having lift block 46 thereon for guiding the bail 34 toward the vertical center line of support housing 18 when the bail is lifted.

55 In operation, when it is desired to lift the grab bucket from a resting position with the bucket halves closed, as shown in Figure 1, the crane operator manipulates the bail 34 so that it is lifted along the vertical center line of the support housing 18 away from the lift block 46. This permits the chains 36 to lift the inner ends of the lever arms 32 and keep the inner edges of the bucket 60 halves together. When it is desired to open the grab bucket after it has been lowered to rest on a surface, the crane operator moves the bail horizontally toward the side of the support housing 18 on which the lift block 46 is located. Then further raising of bail causes the lower shoulders 44 to be engaged by the lift block 46 so that slack is created in chains 36 and further lifting of bail 34 causes the bucket halves to pivot on the lower ends of the rigid support rods 26 and open, as best shown in Figure 2. Then after the grab bucket has been emptied 65 it is again lowered and the bail moved away from lift block 46 so that it can be raised along the center line of

support housing 18 to effect raising of the hinged flanges and closing of the bucket halves 6.

Thus, in operation the grab bucket of the invention is carried by a single crane lift hook and the bucket can be opened and closed when it is resting on a supporting surface by shifting the position of the bail horizontally in the support housing 18. In the closed position, as shown in Figure 1, the grab bucket of the invention is supported by the chains 36 attached to the bail 34. In the open position, as shown in Figure 2, the bucket is supported by the rigid supporting rods 26 through pivot pins 24, support housing 18, lift block 46, and bail 34. In use, e.g. for removing sludge from the bottom of a pickling tank, the open bucket is lowered into place on the sludge in the bottom of the pickling tank. While the bucket is resting on the sludge in the bottom of the tank lift hook 4 is lowered to allow the upper shoulders 42 of the bail 34 to rest on the top of the housing 18, as best shown in Figure 5. In this position the shoulders 44 of bail 34 are not engaged with lift block 46 and horizontal movement of the lift hook 4 will move the bail 34 out of position with respect to the lift block 46. After the lift hook 4 has been moved horizontally to permit the bail to clear the lift block the lift hook 4 is raised and as tension is applied to chains 36 the bucket halves close around the load. After the load has been conveyed to a dumping station the bucket is opened by reversing the sequence of the steps followed in picking up the load.

While one embodiment of my invention has been shown and described, it will be apparent that other adaptations and modifications may be made without departing from the scope of the following claims.

I claim:

1. A grab bucket comprising a pair of hinged bucket halves having inner edges adapted to mate so that said halves form a receptacle when brought together, said bucket halves each having spaced side walls and an outer wall extending between the bottom and outer edges of said side walls, the side walls of one of said bucket halves being hinged together with the side walls of the other of said bucket halves at the upper ends of said inner edges, a support housing disposed above said bucket halves, a bail above said bucket halves adapted to be suspended from a lift hook with a portion thereof disposed for vertical and horizontal movement in said support housing, means providing a releasable connection between said bail and said housing, a pair of flexible elongated support means suspended from said bail, a pair of elongated rigid support means depending from said support housing, means connecting said rigid and flexible support means to said bucket halves with the lower ends of the flexible support means spaced inwardly of the lower ends of the rigid support means, said flexible support means being of such length relative to the rigid support means that the flexible support means are inoperative when the

parts of said releasable connection are connected, said rigid support means being of such length relative to the flexible support means that the rigid support means are operative when the parts of said releasable connection are connected to support said bucket halves adjacent the outer walls thereof so that the bucket halves remain open and the receptacle is not formed when the bail is raised.

2. A grab bucket as defined by claim 1 in which said means connecting said rigid and flexible support means to said bucket halves includes a transverse shaft rigidly mounted in each of said bucket halves, each of said shafts being rigidly supported by its ends in the spaced side walls of its respective bucket half and extending therebetween, at least one lever arm rigidly mounted intermediate its ends on each of said shafts and extending normal to the shaft, said rigid elongated support means being pivotally connected with the ends of said lever arms toward said outer walls, and said flexible elongated support means being connected with the ends of said link arms toward said inner edges.

3. A grab bucket as defined by claim 1 in which each of said elongated rigid support means includes a pair of spaced rods, one of said pairs of rods being connected with one of said bucket halves and the other one of said pairs of rods being connected with the other of said bucket halves.

4. A grab bucket as defined by claim 1 in which each of said flexible elongated support means includes a pair of spaced cables, one of said pairs of cables being connected with one of said bucket halves and the other one of said pairs of spaced cables being connected with the other of said bucket halves.

5. A grab bucket as defined by claim 1 in which said means providing said releasable connection includes a bottom slotted vertically split lifting block fixedly disposed on the upper portion of the inner wall of said support housing on one side of the vertical center line of the support housing, said bail having lateral shoulders thereon adapted to be selectively engaged in the slot of said lifting block.

6. A grab bucket as defined by claim 5 including a vertically split curved guide rib projecting from the inner wall of said support housing on the side of the vertical center line of said support housing remote from said lift block, said rib being adapted to selectively guide said bail to the vertical center line of said support housing away from said lifting block when the bail is raised relative to the support housing.
